UNITED STATES PATENT OFFICE.

BRUNO MARTIN, OF SAGINAW, MICHIGAN.

BLOWTORCH.

Application filed December 7, 1927. Serial No. 232,925.

This invention relates to certain new and useful improvements in blow torches, and it has for an object, among others, to provide simple and efficient means whereby I 5 obtain a stronger heat in the burner, thus constituting what I term a strong generation burner.

It has for a further object to provide a burner having brass piping filled with reticulating material such as rolled up brass wire-cloth so that as soon as the burner gets hot the heat is quickly conducted to the brass piping and this materially helps the oil to get hot in the tank and forms a gas pressure to the 15 burner whereby the operator does not have the trouble to pump up as often as before, the iron pipes readily cool off as it is well-known in this art.

It has for a further object to provide 20 means for protecting the burner against being smoked up with grease or soot. This I term the "oil grease consuming plate".

Other objects and advantages of the invention will hereinafter appear and the novel 25 features thereof will be particularly pointed out in the appended claims.

The invention, in its preferred form, is clearly illustrated in the accompanying drawings, which, with the numerals of reference marked thereon, form a part of this 30 specification, and in which:—

Fig. 1 is a top plan view of my improved blow-torch.

Fig. 2 is a side elevation of the same.

35 Fig. 3 is a longitudinal vertical section on the line 3—3 of Fig. 1.

Fig. 4 is a vertical section on line 4—4 of Fig. 2.

40 Fig. 5 is a vertical cross-section on the line 5—5 of Fig. 2.

Like numerals of reference indicate like 45 parts throughout the several views.

Referring to the drawings: 1 designates a tank of any well-known approved form 50 of construction, shape and size, as best adapted for the purpose and use to which the burner is to be put.

Rising from the tank is the pipe 2, the 55 lower end of which is retained therein in any suitable manner, and upon this pipe is detachably mounted or otherwise retained, the drip cup 3. In this instance, the drip cup is shown as provided with the upwardly extending boss 4, into which is detachably 55 screwed the tubular member 5 on which is mounted the tubular member 6 supporting mem-

ber 6. This member 6 is shown in vertical section in Fig. 4. It is provided with the externally threaded extension 7 which receives the threaded cap nut 8, through which the valve stem 9 is suitably attached. The valve stem is provided with a suitable handle or wheel 10 as seen in Figs. 1, 2 and 3, which wheel or handle may be of any approved or well-known construction. 65

The valve stem is threaded as seen at 11, passing loosely through the bore 12 of the member 6 and having threaded engagement as at 13 with threads in the bore of the member 6, as seen clearly in Fig. 3. The bore 70 14 is closed at its inner end by a removable threaded plug 15 as seen best in Fig. 3, and the pointed end 16 of the valve stem is received within the tapered opening 17 of the said plug, all as clearly seen in Fig. 3. 75

The burner tube 18 has detachable threaded engagement as at 19 with the inner end of the member 6, a suitable packing or washer 20 being interposed between the inner end of the burner tube 18 and the adjacent face of the member 6, all as clearly seen in Fig. 3. The burner tube 18 is provided with radial openings 21 as seen in Fig. 3, as well as in Figs. 1 and 2, and is also longitudinally corrugated as seen at 85 22 in Figs. 1 and 2. This burner tube may be made of any suitable material and of any desired length and diameter.

Mounted upon the member 18 is a member 23, secured to the upper face of the barrel by the screw 24, see Fig. 3, and this member 23 has an offset as at 25 in which is seated the member 26 which bears upon the top of the reduced portion of the member 23, and extends over the band or clip 27 which is seated in a depression 28 in the upper face of the member 23, which clamp or band embraces the burner tube 18 as shown, the lower ends being brought into parallel ends as will be readily understood with reference to Fig. 2, and these parallel ends 29 are held together in clamping position about the burner tube 18 by suitable bolts 30 and nut 31 as seen in Fig. 2. 95

Mounted upon the upper face of the member 23 and disposed above the longitudinal member 26 is the member 32, the upper end of which is forked as at 33, while resting upon this member 32 at the other end is the member 34, which is in the form of an open hook 35, it being understood that the tools to be heated are supported in the fork 33 and 100 105 110

in the member 35 in the usual manner. The screw 24 passes through the overlapped portions of the members 32 and 34, as seen clearly in Figs. 2 and 3.

5 The member 26 is loosely mounted upon the screw 36 so as to be turned upon the same as a pivot to be moved from side to side, its outer end being turned at substantially right angles to its length, as seen at 37 and upon 10 this portion 37 is detachably mounted the horizontally disposed cup-shaped member 38 retained in position thereon by suitable screw 39 and thumb-nut 40, so it may be readily removed when desired.

15 This forms a safety-combustion guard and constitutes a preventor against igniting nearby articles and hence as a fire protector. It is also a protection against wind when the burner is in use. As seen in Fig. 3, it is provided with a slanting curved rim 41 to catch the unburned oil when the torch is put into 20 operation and to keep the flame from igniting the oil in the drip-cup.

As shown in Fig. 4, the member 6 is 25 formed with multiple passages 42, 43, 44, 45 and 46. In these passages is located brass wire cloth or the like 47, which may or may not be twisted, but preferably the latter as shown in Fig. 4. These passages are closed 30 at their outer ends by plugs 48, preferably screw-threaded as seen in Fig. 4. One of these, 48^a, which is disposed in alignment with the passage 52, is adjustable.

These passages are in communication 35 through a passage 49 with the chamber 50 within the member 6, which in turn is in communication with the pipe 2, as seen in Fig. 4, by means of the passage 51, while another passage 52 affords communication

with the bore 14 as seen in Figs. 3 and 4. 40 The outlet of this passage into the burner tube is controlled by the valve 16.

This particular construction of the member 6 serves to consume the gum from the 45 oil and enforce a stronger clear stream of gas to the outlet of the burner, and produces a very strong gas generation burner by reason of obtaining a much greater and stronger heat in the burner tube.

In some instances I may employ a wire 50 gauze or analogous filter 53 in the pipe 2 as seen in Fig. 3, for obvious purpose.

The handle or wheel 10 may be of wood or have a suitable protector in case the same should get exceedingly hot.

Modifications in detail may be resorted to without departing from the spirit of the invention or sacrificing any of its advantages.

What is claimed as new is:—

1. In a blow torch, a burner tube, a supporting member therefor, said member being formed with a bore and a lateral passage therefrom, and multiple passages intersecting each other and opening through the walls of said member, said member having an interior chamber in communication with an oil feed pipe and with said passages. 60

2. A structure in accordance with claim 1 in which said passages have therein a filtering material." 65

3. A structure in accordance with claim 1 in which is included a reticulated medium in 70 said passages, and independent removable closures for said passages permitting ready access to the interior thereof.

75 In testimony whereof I affix my signature.

BRUNO MARTIN.
